CLAIM

The ornamental design for a hand orthosis as shown and described.

DESCRIPTION

FIG. 1 is a front view of a hand orthosis, shown in condition of use;

FIG. 2 is a left perspective view of the hand orthosis of FIG. 1, shown in condition of use with the buckle opened;

FIG. 3 is a rear of the hand orthosis of FIG. 1, shown in condition of use;

FIG. 4 is a left perspective view of the hand orthosis of FIG. 1 thereof;

FIG. 5 is a right perspective view thereof;

FIG. 6 is a bottom, rear, right perspective view thereof;

FIG. 7 is a rear view thereof;

FIG. 8 is a left view thereof;

FIG. 9 is a top view thereof; and,

FIG. 10 is a bottom view thereof.

The claimed design shows an orthosis. In the drawings, the broken lines depict portions of the orthosis and form no part of the claimed design. The broken lines showing a hand in FIGS. 1, 2 and 3 depict environmental subject matter and form no part of the claimed design. All broken lines form no part of the claimed design.
